H. TRENCHAM

INSULATED TERMINAL FOR ELECTRICAL APPARATUS

Filed July 29, 1920

Inventor:
Henry Trencham
by *Arthur G. Davis*
His Attorney

UNITED STATES PATENT OFFICE.

HENRY TRENCHAM, OF RUISLIP, ENGLAND, ASSIGNOR TO GENERAL ELECTRIC COMPANY, A CORPORATION OF NEW YORK.

INSULATED TERMINAL FOR ELECTRICAL APPARATUS.

Application filed July 29, 1920, Serial No. 399,944, and in Great Britain January 3, 1920.

This invention relates to the insulation of terminals of encased electrical apparatus such, for instance, as transformers, and particularly to connecting and disconnecting arrangements wherein one of the parts to be connected is carried by an insulator or bushing of recessed shape, which is surrounded either partly or entirely by grounded material, such as a grounded metal casing, the casing being formed to receive the bushing. With such a recessed bushing or insulator, it is well known that electrical discharges of a brush or corona nature take place very easily from the edge of any conductor carried therein, resulting in decreased safety and leading to danger of breakdown.

The object of this invention is to provide an improved construction of insulated terminal device which will prevent such discharges taking place, and to that end it consists in providing a combined metal sheath and bushing, the sheath being connected to a terminal within the bushing and placed so as to surround the terminal and project beyond it.

The annular space contained between the terminal and the surrounding sheath is filled with insulating material so that the edges of the sheath are entirely embedded therein. As is well known, the provision of such a sheath arranged as described will relieve the inner terminal of the electrical stress which would otherwise produce the discharge referred to, and will transfer such stress to the edge of the sheath. As the edge of this sheath is entirely embedded in insulating material to the exclusion of all air, no brush or corona discharge can take place, and consequently no ionization of the air in the neighborhood of the terminal can occur.

The invention will be more clearly understood by reference to the accompanying drawing, the single figure of which shows a cross-sectional view of my insulated terminal device.

With reference to the drawing, 1 is an insulator body mounted in a grounded metal casing 2, which may be, for instance, a portion of a transformer casing.

50 The insulator comprises a body provided with a central bore 3, one end of which is

expanded to form an enlargement or chamber 4. In the end of the insulator body opposite the enlarged portion of the bore, and concentric with the smaller portion 55 thereof is a cavity 5 in which is located a metal sheath 6 electrically connected as by conductive strips 7 with a conductor terminal 8 located in the smaller end of the bore 3.

60 The metal sheath 6 preferably projects a little beyond the lower end of the terminal member 8, and is embedded in insulating material as illustrated, the space 5, in the rear of the insulator, being filled with an 65 insulating compound, as shown.

In installing my device, a conductor or cable from the transformer or other electrical apparatus within the main casing is secured by soldering or otherwise to the terminal 8 which may be detached from the remainder of the device while this is being done. The terminal 8 is then brought into place within the bushing or insulator 1 and the strips 7 bolted thereto, the strips 7 serving 70 to maintain the terminal in position as well as to connect it electrically with the sheath 6. The space 5 is then filled with enough insulating compound to cover the sheath 6, strips 7 and the bolts and upper 75 end of the terminal 8, this compound effectively preventing corona over the surfaces of the conductive parts covered thereby.

In the embodiment illustrated, the insulator is in one piece and shaped especially 80 to allow for the required construction of the terminal and sheath, but it will be understood that the insulator may be built up from more than one part to facilitate manufacture and assembly, and the arrangement 85 may be modified in other ways without departing from the spirit of my invention, the scope of which is set forth in the appended claim.

What I claim as new and desire to secure 90 by Letters Patent of the United States, is:—

An insulated terminal device comprising 95 an insulator body having a central bore, a metal casing surrounding said insulator body, a terminal mounted in one end of said 100 bore, a conductor connected to the outer end of said terminal, said insulator body hav-

ing a cavity concentric with said bore and open at the end of said insulator body in which the terminal is mounted, a metal sheath located in said cavity and electrically connected to said terminal, said metal sheath surrounding the inner end of said terminal and insulating material sealing said sheath into said cavity and extending beyond the outer end of said terminal to seal the space between said conductor and the surrounding metal casing.

In witness whereof, I have hereunto set my hand this twelfth day of July, 1920.

HENRY TRENCHAM.
